UNITED STATES PATENT OFFICE.

WALTER F. TROTTER, OF CINCINNATI, OHIO, ASSIGNOR TO DETROIT STOKER COMPANY,
OF DETROIT, MICHIGAN, A CORPORATION OF MICHIGAN.

REFUSE-BURNING FURNACE.

Application filed June 27, 1921. Serial No. 480,622.

To all whom it may concern:

Be it known that I, WALTER F. TROTTER, a citizen of the United States of America, residing at Cincinnati, in the county of 5 Hamilton and State of Ohio, have invented certain new and useful Improvements in Refuse-Burning Furnaces, of which the following is a specification, reference being had therein to the accompanying drawings. 10 The invention relates to refuse burning furnaces and has for its object the adapting of an automatic stoker furnace to the alternative use of burning refuse or operating with other fuels. To this end the invention 15 consists in the peculiar construction of air tuyères and means for controlling the same, as hereinafter set forth.

In the drawings:

Figure 1 is a cross-section through the 20 furnace;

Figure 2 is a sectional plan view thereof;

Figure 3 is a sectional view taken on line 3—3 of Figure 2;

Figure 4 is a detail perspective view of 25 one of the tuyère blocks detached and showing parts broken away;

Figure 5 is an enlarged fragmentary sectional view of one of the corner blocks.

A is the front wall, B the side wall and 30 C the rear wall of a furnace which is provided with any suitable construction of grates and stoker. As shown, the stoker comprises a trough-shaped retort D and grate bars E extending from said retort towards the side walls of the furnace, over 35 which the fuel lifted from the retort is fed to the ash holders F.

Where the furnace is designed for the burning of refuse, it is preferably provided 40 with closed grates to prevent the sifting of unburnt material between the same and this necessitates the supply of air through some other channel. I have therefore arranged air tuyères in the side wall B of the furnace, which extend along the same in a recess therein and in a position just above the ash holder. These tuyères occasionally burn out and must be renewed and I have 45 devised a construction which permits of detachment and replacement.

In detail, the tuyères are formed of hollow blocks or sections G, which, as shown in Figure 4, are of substantially rectangular form open at their opposite ends and having laterally discharging ports H in the

side towards the furnace chamber. The blocks are interlocking engaged with each other by a flange I at one end thereof extending inward into the adjacent block. The opposite end of the block has a narrow 60 portion J for receiving said flange and inward from this narrow portion the block is cut away on an incline K. This permits of swinging each block into and out of engagement with adjacent blocks without disturbing the latter, as indicated in dotted lines at L in Figure 2. The blocks are also reinforced by longitudinally extending ribs M cast integral therewith and projecting inward, these serving not only to reinforce the 70 blocks but also to assist in conducting away the heat.

At the forward and rear ends of the furnace hollow blocks of similar form but without the ports H are employed, as indicated at N and O. Similar blocks extend across the rear wall of the furnace, as indicated at P, and a corner block Q forms the connection therebetween. R is a port in the rear wall located below the grates and communicating with the sections P, whereby air may be fed from said port through the entire series of tuyères. To control the air supply, a damper or shut-off valve is arranged in the conduit, preferably in the 80 corner block Q and which, as shown, comprises a swinging gate valve S pivotally mounted on a pin T and connected by the apertured ears U with a rod V extending through the blocks G to the front of the 90 furnace. Thus by adjusting the rod V longitudinally the damper may be either opened or closed or adjusted to any desired position for restricting the draft.

With the construction as described the 95 refuse is fed into the furnace chamber from a feed port (not shown) at the top and will fall upon the grates and burning fuel thereon. The air which is admitted through the tuyères will be directed over 100 this refuse and will support combustion, the amount being regulated by the rod V and damper S. If at any time one or more of the tuyère sections burns out, it can be quickly pulled out of the recess and replaced 105 by a new section.

While I have described the furnace as particularly adapted for refuse burning, the arrangement of the tuyère or air channel above the grates and in the wall, which is 110

adjacent to the ash discharge, is advantageous where other fuels are used. Thus the discharge of air at this point not only provides warm air for supporting combustion, but it also serves to cool the wall and to prevent the adhesion of clinkers thereto.

What I claim as my invention is:

1. In a furnace, the combination with a furnace wall, of a tuyère located in a recess in said wall comprising a plurality of removable hollow substantially rectangular open-ended sections engaging each other at the ends thereof and having laterally opening ports, each of said sections being cut away at one end to provide for clearance for detaching the same without disturbing the adjacent sections.
2. In a furnace, the combination with a wall thereof, of a tuyère located in a recess in said wall comprising a plurality of removable hollow substantially rectangular open-ended sections engaging each other at the ends thereof and providing a continuous face adjacent to the furnace chamber with laterally opening ports therethrough, each of said blocks being obliquely cut away at one end in the portion within the recess to provide clearance for swinging said block outward without disturbing the adjacent blocks.
3. In a furnace, the combination with a wall thereof, of a tuyère located in a recess in said wall comprising a series of substantially rectangular hollow open-ended sections, each section having at one end thereof a flange for engaging the recess of an adjacent section and at its opposite end a narrow portion for being engaged by a similar flange on the adjacent section, said section at the latter end being cut away obliquely to provide for the swinging of the section outward without disturbance of adjacent sections.
4. In a furnace, the combination with a furnace wall, of a tuyère located in a recess in said wall comprising a plurality of hollow open-ended sections provided with ports for discharging air into the furnace chamber, a damper locate in one of said sections for cutting off or restricting air communication, and a rod extending through a plu-

rality of sections adapted to actuate said damper.

5. In a furnace, the combination with a furnace wall, of a tuyère located in a recess in said wall comprising a plurality of hollow open ended sections having laterally opening ports, each of said sections being cut away at one end to provide clearance for detaching the same without disturbing the adjacent sections, each of said sections also having a projection at the opposite end extending within the adjacent section.

6. In a furnace, the combination with a wall having a recess therein, of a tuyère located in said recess and comprising a series of independently removable hollow open ended sections interlocking each other at their ends and having lateral ports, a damper in one of said sections, and removable operating means for said damper extending through the other sections, said operating means normally preventing the removal of said sections from the recess in said wall.

7. In a furnace, the combination with a wall having a recess therein, of a tuyère located in said recess and comprising a series of hollow open-ended sections arranged end to end and having laterally opening ports, a damper in one of said sections, and means extending through the other sections for normally holding said sections together and for operating said damper.

8. In a furnace, the combination with a wall having a recess therein, of a tuyère located in said recess and comprising a series of removable hollow interlocking sections having laterally opening ports, a damper in one of said sections, and a removable rod extending through the other sections for operating said damper, said rod normally preventing removal of said sections from the recess in said wall.

9. In a furnace, the combination with a furnace wall, of a tuyère located in a recess in said wall and including a plurality of independently removable hollow open ended sections interlocking each other at their ends and having laterally opening ports.

In testimony whereof I affix my signature.
WALTER F. TROTTER.
